Atty.

UNITED STATES PATENT OFFICE.

KATIE RYAN, OF ST. PAUL, MINNESOTA.

BICYCLE-SKIRT.

SPECIFICATION forming part of Letters Patent No. 651,389, dated June 12, 1900.

Application filed May 5, 1899. Serial No. 715,762. (No model.)

To all whom it may concern:

Be it known that I, KATIE RYAN, a citizen of the United States, residing at St. Paul, in the county of Ramsey and State of Minnesota, have invented certain new and useful Improvements in Bicycle-Skirts, of which the following is a specification.

My invention relates to improvements in dress-skirts of that class which are adjustable in length, and has for its object to provide a skirt the lower part of which can be raised or lowered evenly at all points and in which the lifting devices shall be concealed.

In the accompanying drawings, Figure 1 is a perspective view of the garment complete, showing the inner skirt in raised position, the lifting devices being indicated by dotted lines. Fig. 2 is a similar view of the complete garment, showing the inner skirt in lowered position; and Fig. 3 is a similar view of the inner skirt and its attached lifting devices.

The garment is preferably a two-part garment, comprising an outer skirt A', provided with the usual waistband or belt A², and an inner skirt B³, suspended from within or secured to the outer skirt near the waist-line. The outer skirt is the shorter and of suitable length for bicycling, outing, or similar use. The inner skirt B³ is made, preferably, of thin and flexible material and is provided at the bottom with a band B' of the same material as the outer skirt.

At a suitable distance below the waist-line, but preferably along its line of connection with the bottom band B', the inner skirt is provided with a number of sections or lifting-pieces B², preferably triangular in shape, of cloth or other flexible material, each lifting-piece being secured along one edge to the inner skirt and so positioned that the ends of the secured edge of each lifting-piece shall nearly or quite meet the adjacent ends of the secured edges of the adjacent lifting-pieces to form a substantially-continuous line of attachment all around the skirt. To the free corners of these lifting-pieces are secured lifting-cords a' a², extending upwardly through openings or eyes a³ in the waistband or belt A² of the outer skirt, the upper ends of these lifting-cords being secured to the belt or to each other in any desired way.

When the lifting-cords a' a² are drawn up to raise the lower part of the inner skirt, the pull is transmitted through the medium of 55 the lifting-pieces to every point along the line of their secured edges, so that the lower part of the skirt is raised evenly and uniformly all around. The lifting-cords may then be looped or fastened in any desired way. When 60 so drawn up until its lower edge is even with the lower edge of the outer skirt, the inner skirt will be entirely within and concealed by the outer skirt, as shown in Fig. 1. When the cords are released, the inner skirt will 65 drop and form a regular long skirt, the lower band B' appearing to be a continuation of the outer skirt.

By providing an outer skirt A', I am enabled to secure the lifting-pieces B² upon the 70 outside of the inner skirt B³, to lead the lifting-cords conveniently from within out through the eyes in the belt of the outer skirt, and to make the upper part of the inner skirt of easily-collapsible material, for this part of 75 the inner skirt and its attached lifting-pieces and lifting-cords will be entirely within and concealed from view by the outer skirt.

Having now described my invention, what I claim as new, and desire to secure by Letters 80 Patent, is—

1. A dress-skirt of the class described, provided with a plurality of triangular lifting-pieces, each secured along one edge to the skirt, the secured edges of the lifting-pieces 85 forming a substantially-continuous line around the skirt, the free corners of said lifting-pieces having lifting-cords attached thereto.

2. A double dress-skirt, the outer skirt being the shorter, provided with a plurality of lifting-pieces, each secured along one edge to the inner skirt, the secured edges of the lifting-pieces forming a substantially-continuous line around the inner skirt, said lifting-pieces being provided with lifting-cords 95 working between the skirts and passing through the waistband.

Dated this 2d day of May, 1899.

KATIE RYAN.
